UNITED STATES PATENT OFFICE.

FRANK WASHBOURNE, OF BROOKLYN, NEW YORK.

DESIGN FOR AN UMBRELLA TIP-CUP.

Specification forming part of Design No. **11,475**, dated October 28, 1879; application filed September 8, 1879.
[Term of patent 3½ years.]

To all whom it may concern:

Be it known that I, FRANK WASHBOURNE, of the city of Brooklyn, in the county of Kings and State of New York, have originated and invented a new Design for Umbrella Tip-Cups, of which the following is a description, reference being had to the accompanying drawings, making part of this specification.

To explain the drawings, I will first state that what is known in the trade as an "umbrella tip-cup" commonly consists of two parts—viz., the cup proper, (indicated by A,) and the inside collar, (indicated by B.)

Figure 1 is a side view of the cup proper, and Fig. 2 a side view of the cup and the collar on which it is placed, showing the appearance of the complete tip-cup.

The cup proper A is in the form of a short cylinder, as indicated by A, with its ends

rounded at the edges in ovolو form, as shown at *a a*, and it has, close to where the rounding-off commences at each end, a circumferential sink or recessed line or narrow groove, *c*.

Between the lines *c c* the cup may be plain or ornamented by engraving.

What I claim as my invention, and desire to secure by Letters Patent, is—

The design for an umbrella tip-cup of the configuration described, consisting, essentially, of the cylinder A, with the rounded or ovolو-formed edges *a a* and circumferential recessed lines or grooves *c c*, as shown in the accompanying drawings.

FRANK WASHBOURNE.
